HARMONICA

Anthony La Paglia, New York, N. Y.

Application February 19, 1948, Serial No. 9,381

1 Claim. (Cl. 84—377)

1

My invention is an improvement in musical instruments; and more especially harmonicas, or "mouth organs" as they are popularly called.

An important object of my invention is to provide a harmonica containing all the necessary parts but so constructed that it can be quickly and effectually repaired in case of damage involving any of the vibrating elements or reeds on the interior thereof.

Harmonicas are usually made with an elongated hollow body or casing enclosing a chamber having a longitudinal partition in the middle and a number of transverse partitions rigid with the longitudinal one to divide the inside space into cells. The sides are closed by metal plates affixed to the body, and in contact with the opposite ends of the transverse partitions. These plates have transverse slots therein, one for each cell and parallel thereto; and attached to the sides are vibratable tongues or resilient strips of metal, made fast at one end and free at the other; one for each slot and substantially coinciding therewith; and extending lengthwise of the same. If one of the tongues or "reeds" is impaired, the side plate must be dismounted and the faulty tongue removed and replaced, or a whole new side plate substituted.

This design has proved very unsatisfactory, because the article develops internal stresses in actual use; and when a side is taken off, such stresses are apt to become unbalanced and distortion of partitions forming the cells ensues. This condition often arises when the partitions are of wood, because the wood is moistened when the instrument is played, and dries later, and then easily warps. Whenever a side plate is loosened, the warping becomes very pronounced and the harmonica may be rendered useless.

With my invention these disadvantages are overcome and the replacement of any one of the tongues can be accomplished immediately without any detrimental effect upon the continued usefulness of the instrument. In its preferred embodiment the cells having the tongues or "reeds" are complete independent units; so disposed in the casing that each of them can be easily and quickly inserted or extracted, as may be needed.

Another object is to provide a harmonica of the character above outlined that is simple and inexpensive to produce, durable in character and capable of long and perfect service.

The nature of the invention is made plain in the following description and the novel features are pointed out in the claim at the end hereof.

But the design shown is explanatory only and numerous variations in details may be adopted without departure from the general plan in which the invention resides.

On the drawings,

Figure 1 is a side elevation partly in section of a harmonica according to this invention;

Figure 2 is a bottom plan thereof;

Figure 3 is a top plan of same;

Figure 4 is a cross section on line 4—4 of Figure 1;

Figure 5 is a perspective view of one of the unitary tubular cells carrying the vibrator tongues or reeds which produce the sounds of the instrument;

Figure 6 shows a detail used with my invention; and

Figure 7 is a perspective view of a modification.

The harmonica has a body made of a perforated top strip or member 1, of plastic or any other suitable material, affixed to end members 2, bridged by side plates 3 affixed to the members 2. The top member presents large apertures 4, arranged in a row between the ends of the member 1; and screws 5 are employed to fasten the ends 2 and the member 1 together. The top, ends and sides enclose a long chamber, preferably open at the bottom, to receive the tubular cells 6. Each cell contains two longitudinal passages separated by a central web or partition 7 therein, and running the full length of the cell. The partition has a longitudinal slot 8, and on one face of the partition or plate 7, overlying the slot is a vibrator tongue or resilient metal strip 9, held in place on the partition or plate 7 by a rivet 10. The two passages are indicated by the numerals 11 and 12. Each is closed at one end by a plug or closure 13, the plugs being inserted into opposite ends of the cells 6. Hence air blown into the cell by way of the passage 12, for example, must flow through the slot 8 and cause the tongue or reed 9 to flutter as the air is discharged from the other passage 11. The cells are so disposed in the casing that the open ends of the passages 12 and the closed ends of the passages 11 are in proximity to the member 1 and the apertures 4 therein.

The cells 6, all of the same size and shape, are slipped into the casing at the bottom, with the tongues 9 pointing towards the member 1. The cells are disposed in two coextensive rows or layers from end to end of the casing and between the sides 3. The rows are thus made up of successive cells in transverse pairs and the partitions or webs 7 of each pair of cells in the

two longitudinal rows are in alignment with each other. All the cells present the closed ends of the passages 11 and the open ends of the passages 12 to the top member 1, as already stated. But beginning at the left end of the harmonica as seen from below in Figure 2, the first pair of cells have their passages 12 closer to the adjacent end member 2. The next pair of cells, however, have their passages 11 closer to said end 2. Each successive pair to the right is similarly reversed with respect to the preceding pair. In this arrangement any transverse pair of cells can be extracted by means of a pair of pliers with thin jaws or any other suitable tool inserted at the bottom of the body 1 into the open ends of the passages 11. Likewise any two cells in each row, except the cells at the ends thereof, can be pulled out together. Hence the cells can be easily examined and if any are found to be defective, new ones can be substituted.

While the bottom of the casing is illustrated as open, a suitable removable cover can of course be attached to it.

The edges of the side plates 3 adjacent the member 1 are connected by a fixed longitudinal channel strip 14 with flanges 15 overlapping the outer faces of the plates 3. The strip 14 and plates 3 are made fast by welding, solder or in any other feasible way. The strip 14 has two rows of apertures 16 extending lengthwise; a row of apertures being above each longitudinal row of cells 6; and with the apertures of each row as large and as far apart from center to center as necessary to enable these apertures to serve as inlet openings to admit air to all passages 12 in the row of cells 6 with which said row of apertures or openings 16 is associated. On the strip 14 is a slide member 17, having two rows of openings 18 of the same size and shape as the openings 16. But the apertures 18 of one row, however, are staggered with respect to those in the other, as portrayed in Figure 3. The member 17 can be manipulated so that the openings 16 of only one row in the strip 14 can be fully uncovered by bringing the openings 18 in registry therewith; but part of each aperture 18 in both rows can be exposed all at one time if desired.

The slide member 17 is overlaid by a second channel strip 19 having flanges 20 as far apart as the edges of the member 17, overlapping the slide 17. The strip 19 is secured to the strip 14 along its said flanges; and the member 17 can be moved longitudinally between the strips 14 and 19. The fixed strip 19 has two rows of apertures 16' registering with the opening 16 in the strip 14 and of the same size and shape as the latter.

The slide member 17 has a projecting end with a handle 21 so that it can be urged in one direction by the player; this handle being bent laterally to be pressed with a finger. In the adjacent end member 2 is a recess 22 containing a U-shaped spring 23 with one end entering a small opening in the member 17. Thus the member 17 is pushed out. The adjacent end of the strip 14 has a slot 24 for the end of the spring 22; and the member 17 has a slot 25, and the adjacent screw 5 securing the member to the end 2 passes through both slots so as not to obstruct operation of the member 17. The sides 70 are held to the ends by fastening devices 26; and the strips 14 and 19 are further held in place by the fastening devices 5.

Upon the side plates 3 are the bent plates 27, also held on by screws or rivets 26. These plates

27 are sometimes called the "skins" and are bent double longitudinally and the space 28 between is open adjacent the bottom of the casing to impart resonance to the notes which the instrument emits.

As indicated in Figure 4, the two rows of cells 6 are divided by a longitudinal metal partition 29, affixed in any suitable way to the end members 3.

As illustrated in Figure 6, valves 30 of rubber or other suitable material may be attached to some of the cells 6 at the extremities remote from the top member 1. These valves are really wind saving devices. The cells which carry them will permit air to be blown through them from the open ends of the passages 12, but will obstruct air moving in the opposite direction. The instrument is played by blowing air through the cells which have these flaps 30, and drawing the air through the remainder of the cells which have no flap valves attached thereto. Harmonicas are usually operated in this fashion.

In Figure 7 the tubular element 6 is of the same construction, but the partition 7' is made in one piece with the ends turned over to form closures at one end of each passage 11 and 12, as indicated at 13'. Therefore plugs or stoppers 13 are unnecessary. Between the reversely bent ends 13' the plate or partition 7' has the same slot 8 and the same reed or tongue 9 secured by a rivet 10.

With the member 7' having reversely bent ends, and with the slot 8 and tongue 9, a harmonica can be produced either by assembling a number of cells in the space between two sides of the body of the instrument, as above described, or by utilizing the members 7 in cells or compartments which are not independent. In other words, a harmonica might be formed with a longitudinal partition in the space enclosed by the sides and ends, such as is shown in 29 on Figure 1, and with transverse partitions of substantially the same size as the cross section of the cells 6. Into the compartments or cells thus formed the members 7 would be inserted. Each one of such cells or compartments would thus be divided into two longitudinal passages closed as shown in Figures 5 and 7, by the turned-over ends 13 of the member 7'. Whenever a reed becomes damaged the member 7' can be taken out and a new one substituted.

The wind saving valves 30 will be utilized with the parts 7' in the same way as before. The unit as illustrated in Figure 7, containing a partition plate with bent-over ends may of course also be employed in the same way as the unit in Figure 5 to fill the space inside of the body of the mouth organ, consisting of the ends 2 and sides 3. That is, the cells 6 with the partitions 7' may be so inserted that the cells can be removed, or only the partition 7' extracted.

Having described my invention, what I believe to be new is:

A musical instrument comprising an elongated top member, end members secured to the extremities of the top member and extending downward therefrom, side plates connected to the top and end members, the bottom of the instrument being open between the end members and the plates, a fixed strip between the top member and the side plates, said strip having flanges along its opposite edges engaging said plates and said end members, said strip having two rows of longitudinal openings arranged in transverse pairs, and cells having partitions, said cells being sub-

stantially square in cross section and disposed side by side and extending in a double row between said plates from one end member to the other, each cell being in line with one of said openings and removable through the bottom, each cell also having one end adjacent said strip and the other end overlapped by the side plates at the bottom of the instrument, each cell having a part of one end open at one side of its partition and the remaining part of said end on the other side of said partition closed and a part of its opposite end on the one side of said partition closed, the remaining part of said opposite end on the other side of said partition being open, said top member having a longitudinally extending row of relatively large openings each of which spans a pair of openings in said strip, said instrument also having an adjustable slide member in the top member adjacent said strip, said slide member having two rows of longitudinal apertures in staggered positions, said apertures being so disposed as to register with the openings of either row in said strip and close the remaining openings in said strip, or partly close all the openings in said strip, said instrument having a longitudi-

nal partition between the rows of cells secured to the end members, adjacent cells in each row having the open parts of their ends adjacent, the open parts and the closed parts of the ends of the cells in the two rows being respectively in transverse alignment between said plates, the top member forming a mouth piece for all the cells.
